Fig. 1 represents a perspective view of the stove. A. Fig. 2. represents the large oven door, of which there are two, one being a duplicate of the other, ornamented with a vine branch, from which hangs pendent two leaves C.C, and bunch of grapes D. with spiral tendril E. B. Fig. 2. represents the small oven door, of which there are two, one being a duplicate of the other, ornamented with a vine leaf H.

Fig. 3. represents a panel in the lower front, ornamented with a vine branch, leaf and bunch of grapes I. Fig. 4. represents the fire door, ornamented with a bunch of grapes J. Fig. 5. represents the foot, of which there are four, all exactly similar, ornamented with the leaf K, and the band L. Fig. 6. represents the front doors ornamented with the leaves M and N.

Having thus described my design for plates of cooking stove, what I claim as new therein, and desire to secure by Letters Patent, is,

The ornamental configuration and design for plates of cooking stove, as herein described and shown in the accompanying drawing.
